UNITED STATES PATENT OFFICE.

JOHN SCHUMACHER, OF LOS ANGELES, CALIFORNIA.

PROCESS OF HANDLING PLASTER-BOARD.

1,325,452.

Specification of Letters Patent. Patented Dec. 16, 1919.

Application filed June 2, 1919. Serial No. 301,212.

To all whom it may concern:

Be it known that I, JOHN SCHUMACHER, a citizen of the United States, residing at Los Angeles, in the county of Los Angeles and State of California, have invented new and useful Improvements in Processes of Handling Plaster-Board, of which the following is a specification.

This invention relates to carrying out certain steps in the manufacture of plaster board, wherein the plaster board is delivered vertically, cut into lengths, and stacked on trays or other receiving means in its initially wet condition, allowed to harden, and sub-divided. In my application for "machine for making plaster board and the like", Serial No. 278,186, apparatus for making plaster board and delivering the same from the machine in a vertical direction is disclosed.

According to the present invention, long sheets of plaster board are laid horizontally upon conveyers, the latter reciprocating. The next step consists in sub-dividing the sheets into lengths suitable for handling in the final stages of use of the plaster board. The sub-division of the plaster board is performed while the board is on the conveyer and before it is finally dried. Trimming of the sheets may be performed as a separate step, if desired.

The present invention is especially adapted for use with plaster board formed of a plurality of pieces of paper with an interposed layer of retarded plaster therebetween, the paper being of the character which retards permeation by moisture. Thus, several plaster board sheets may be built up and handled in flexible condition, being stacked in such condition in horizontal position, and then set aside so that the plaster may set or harden. After such setting of the mass, it may be subdivided and trimmed on its longitudinal edges, the cut being taken through all the sheets of plaster board comprising the mass. A perfectly smooth edge may thus be obtained for the plaster board requiring no further trimming of the product before marketing. According to the usual practice, the sub-divided sheets may now be raised on edge and finally dried in spaced relation.

It is obvious that many kinds and types of apparatus may be employed in making the plaster board and in handling the same after manufacture. In the accompanying

drawing, certain apparatus is disclosed for carrying out the process which constitutes the present invention. However, the process is in no way limited to the utilization of this or any particular apparatus. Such apparatus is illustrated in the accompanying drawings, in which:

Figure 1 is a side elevation of apparatus suitable for carrying out certain steps of the process; Fig. 2 is a side elevation of apparatus for carrying out other steps of the process succeeding the steps carried out by the apparatus shown in Fig. 1; Fig. 3 is a plan view of the apparatus shown in Fig. 2, the ends being broken away; Fig. 4 is a fragmentary perspective view showing the guide means used for the apparatus shown in Fig. 1; Fig. 5 is a diagrammatic view in section through the guide means illustrated in Fig. 4; Figs. 6 and 7 are views similar to Fig. 5 showing other positions of the switch; Fig. 8 is an enlarged transverse section through a switch for locking the guide in neutral position; Fig. 9 is a fragmentary side elevation of a modified form of guide means; Fig. 10 is a section taken on the line 10-10 of Fig. 9; Fig. 11 is a side elevation of the complete guide apparatus shown in Fig. 9 and the conveyer cars for co-operating therewith; and Fig. 12 is an enlarged section taken on the line 12-12 of Fig. 11.

Referring particularly to Figs. 1, 2 and 3, A indicates generally a machine for making plaster board B, which is delivered vertically, and laid horizontally upon cars C. As the plaster board passes from the machine, it is severed by a cutter D, the severed ends being guided by guide E. A longitudinal cutting means is indicated by F and a transverse cutting means by G.

Referring particularly to Fig. 1, the plaster board machine consists of a hopper formed by strips of paper 14 carried by endless conveyers 15 which converge toward a discharge outlet. Plaster is fed into the hopper, the plaster board B emerging from the hopper as wet flexible board. The board is fed continuously and passes through a severing mechanism D comprising a cutter way 16 which is reciprocated. Sliding in the cutter way transversely of the board is a cutter 17 which passes through the board from one side to the other. The cutter is operated by suitable mechanism so that it is moved only at the time that the way 16 is traveling with the plaster board and at the

same speed. Thus, the plaster board is fed from the machine continuously and cut without any variation in speed.

- The train of cars C reciprocate under the severing mechanism, and is moved by a chain and associated mechanism indicated generally by 18. The mechanism may be of any convenient form, and therefore, is not described in detail. The movement of the 10 cars and the severing mechanism is so adjusted that a severed end of the plaster board indicated by 19, see Fig. 1, is laid upon a car at one end. Thus, as the train moves to the right as indicated by the arrow α in 15 Fig. 1 the plaster board is spread thereover. As the left-hand car moves under the severing mechanism, the latter is operated to cut the board, and the end is laid upon the car substantially flush with the end of the 20 car. The guide mechanism E is operated to lay the ends of the unsevered sheet upon the end of the length just severed, and guides the new sheet so that it will flow in the opposite direction. The train of cars now 25 moves to the left, and as the right hand car passes under the severing mechanism a cut is made through the board and the end laid upon the car. The guide mechanism is now operated to cause the plaster board to flow 30 upon the car in the opposite direction. This continues until a number of lengths have been laid upon the cars in stacked relation. The plaster board is now allowed to set, after which it is sub-divided and trimmed. 35 Referring particularly to Figs. 2 and 3, a traveling crane 20 is provided with hooks 21, by means of which loaded trays 22 may be handled. The cars C have trays 22 upon which the plaster board is laid. These trays 40 with layers of plaster board thereon are used for bringing the plaster board into desired positions in other steps of its manufacture. F designates trimming means for the longitudinal trimming of the plaster board, and 45 comprises a pair of depending circular saws 23 mounted upon a suitable shaft 24 journaled in a framework 25. The trimming means is positioned over a track 26 upon which the train of cars C moves to convey 50 the plaster board past the saws 23 to trim both edges of the layers. After the layers have been trimmed longitudinally, the train may be stopped at the transverse trimming means G to permit the plaster board to be 55 sub-divided between the cars of the train. The saw 27 of the transverse trimming means is preferably swung from an overhead frame work 28 by means of a swinging frame 29. It is obvious that by subdividing the initial lengths of plaster board in the manner just described, a great wastage of plaster board is prevented. If desired, the sub-dividing may be so performed that no further transverse trimming is required. 60 In Figs. 4 to 8 inclusive a type of guide

means for guiding the plaster board on to the cars is illustrated. The plaster board as it comes from the plaster board machine is wet and possesses no great strength. For this reason, the cars should be brought as close to the discharge of the plaster board machine as possible. It is also desirable that the plaster board be guided upon the cars, and the ends of the initial length laid upon the cars without very much of a drop. 75 In this manner the form and constitution of the plaster board will not be disturbed. It is also advantageous to so guide the severed ends of the plaster board upon the cars that when in stacked relation, the ends will very 80 closely register. Thus, in trimming the ends only a small amount of board is wasted. At the time that the severed ends are laid upon the train, there is a change in direction of movement of the train. Without 85 some guide means, the severed ends would not register. The guide means shown in Figs. 4 and 8 inclusive is designed to properly lay the ends of the plaster board. Although, this mechanism is described in detail, it forms no part of the present invention which is for a method of handling plaster board.

Referring to Figs. 1 to 4, a hanger frame 30 is shown. Journaled in the frame is a 95 switch member 31. Switch member 31 is a triangular prism having two curved faces meeting in an apex pointing upwardly. A trunnion 34 has a segmental pinion 35 fixed thereto. Journaled on a shaft fixed to frame 100 30 is a segmental pinion 36 meshing with pinion 35. Extending from the pinion 36 is an arm 37. Secured to the arm 37 and extending inwardly are tines 38 and 39. It is obvious that by rocking arm 37 the switch 105 member 31 may be rocked. It is desired to rock the switch member in the proper direction as either of the end cars of a train pass thereunder. For this purpose pins are secured to the end cars in such position that 110 they will engage the arm 37 as the cars pass thereunder. A pin 40 is secured to the left hand car adjacent its free end. As the train of cars moves to the right, pin 40 will engage arm 37 and rock the switch member 115 in the direction shown in Fig. 6. As the train of cars reverses its direction of motion, it is desired that switch member 31 be returned to its neutral position as indicated in Fig. 5. The pin 40 will have entered in 120 the space between tine 38 and arm 37, and can not disengage itself until the arm has reached its neutral position as shown in Fig. 7. The pin 41 on the end of the right hand car may engage the arm 37 as the train of 125 cars reaches the opposite end of its travel. In a like manner switch 31 is rocked in the opposite direction and then back to its neutral position. In order to normally retain the switch in neutral position a detent is 130

provided. A hollow projection 42 has a pin 43, see Fig. 8, which is adapted to engage a recess in shaft 34. Pin 43 is held in its lower position by a spring 44 which engages 5 a plug threaded into the top.

Assume that the switch is in its neutral position as shown in Figs. 4 and 5 and that the train of cars is moving in the direction of the arrow α . Plaster board is flowing 10 over the face 33 of the switch and being laid upon the cars. As the free end of the left hand car approaches the severing mechanism, the latter operates to make a cut indicated by 46 in Fig. 5. The pin 40 now engages 15 the arm 37 and rocks the switch presenting the face 32 to the end of the depending plaster board which as it leaves the machine flows over the other side of the switch. At the same time the end of the sheet of 20 plaster board thus severed slides down over the face 33 as the switch is rocked and lays the latter upon the car. The return movement of the train of cars rocks the switch to neutral position as shown in Fig. 7. The 25 end of the plaster board sheet being discharged from the machine is laid upon the cars so as to register with the ends of the sheets already stacked thereon. At the other end of the travel of the cars the reverse 30 operation occurs.

In Figs. 9 to 12 a modified form of guide means is shown. The switch of a guide means must clear the top of the cars so that they may move thereunder. It must also 35 clear the top of the stack thereon. If the position above the cars is not made adjustable, there will be a greater drop of the ends of the plaster board sheets on to the car for the first layer of a stack than for the last. 40 The form of guide means shown in Figs. 9 to 12 inclusive, is adjustable as to the distance of the switch above the cars.

A frame 47 is mounted in a fixed position. The frame comprises upright channel members 48 serving as guides for blocks 49. The blocks 49 serve as nuts having threaded bores in which are disposed threaded shafts 50. 45 The ends of the shafts 50 are provided with bevel pinions which mesh with bevel pinions upon a shaft 52 which may be operated by a hand wheel. Extending between and secured to blocks 49 is a way 53 having a slot for receiving the roller of a switch. A bar 54 is secured between standards 48 has a bearing at the center thereof. A similar construction for the frame is disposed on the other side, the ways being connected by tie rods 55. Journaled on the bars 54 is a shaft 56, to which is fixedly secured a telescopic switch member consisting of sections 57 and 58. Section 58 carries at its free end rollers 59 riding in the ways. It is obvious 60 that the switch member may be rocked, the lower end thereof being guided in a straight horizontal line by the ways 53, and that the

position of the bottom of the switch member may be adjusted by the hand wheel. To rock the switch member at the proper time an arm 60 is secured to the shaft 56. Connecting rods 61 and 62 are secured to the 70 arms. The end of connecting rod 61 is provided with a pin 63 in a way 64. Secured to the connecting rod is an abutment 65 in the form of a hook, as best shown in Fig. 12. Connecting rod 62 is guided in a way 66 and 75 has an abutment 67 secured thereto. Referring to the cars, on the right hand end there is a pin 68 so disposed that it will clear the opening in abutment 65. On the other end of the train of cars is a pin 69 which 80 will engage the lower end of abutment 65. Pins 68 and 69 are so arranged that pin 68 will engage abutment 67, while pin 69 will clear the same. Thus, the switch is rocked into proper position at the end of the travel 85 of the train of cars in either direction. As the stack increases in height the ways 63 are raised by means of the hand wheel 70, although by suitable mechanism the ways might be raised by the travel of the cars. 90

Although I have shown specific mechanism to carry out the process of handling plaster board, such process is not limited to any particular mechanism.

What I claim is:

1. The process of handling plaster board, which consists in vertically delivering wet plaster board, reciprocating a receiver horizontally thereunder, flowing said plaster board on to said receiver, and severing the 100 plaster board when the receiver reaches the ends of its travel.

2. The process of handling plaster board, which consists in vertically delivering wet plaster board, reciprocating a receiver horizontally thereunder, flowing said plaster board on to said receiver, severing the plaster board when the receiver reaches the ends of its travel, permitting setting of the severed 105 plaster board on said receiver, and transversely sub-dividing the severed plaster board on said receiver.

3. The process of handling plaster board which consists in depositing plaster board in a flexible state upon a horizontally reciprocating receiver, and severing the plaster board when the receiver reaches the ends 115 of its travel.

4. The process of handling plaster board which consists in delivering plaster board in 120 a flexible state upon a horizontally reciprocating receiver, severing the plaster board when the receiver reaches the ends of its travel, permitting setting of the plaster board on said receiver, and transversely sub-dividing the severed plaster board.

5. The process of handling plaster board, which consists in vertically delivering plaster board in a flexible state, reciprocating a receiver horizontally thereunder, flowing 130

said plaster board on to said receiver, severing the plaster board when the receiver reaches the ends of its travel, and switching the direction of flow of said plaster board on 5 to said receiver.

6. The process of handling plaster board, which consists in vertically delivering plaster board in a flexible state, reciprocating a receiver horizontally thereunder, flowing 10 said plaster board on to said receiver, sever-

ing the plaster board when the receiver reaches the ends of its travel, switching the direction of flow of said plaster board on to said receiver, permitting setting of the severed plaster board, and transversely subdividing said severed plaster board. 15

In witness that I claim the foregoing I have hereunto subscribed my name this 23rd day of May, 1919.

JOHN SCHUMACHER.
